ROLLER SKATE ATTACHMENT

Mikaly Galgozy, Cleveland, Ohio

Application January 4, 1938, Serial No. 183,359

6 Claims. (Cl. 280—11.37)

This invention relates to an especially designed and constructed accessory such as may be classified broadly as an attachment, the same being in the nature of a holder for a flashlight adapted to be attached to and suspended from a roller skate. Occasions and conditions arise when it is found desirable to have a source of illumination carried upon and movable with a roller skate while in use. For example, in skating exhibitions where scintillating lighted display is desired, foot and floor illumination is in order. Now, however, since tap dancing on skates has become a fad, it is also the vogue to enhance the effect by illuminated display against darkened backgrounds and the like. It follows therefore, that the present invention relates to a hanger fixture or holder for a so-called self-contained lamp or flashlight, wherein the device is expressly perfected for suspension from the frame 5 of the skate.

The provision of a depending detachable spotlight or so-called flashlight is of course, the jist of the inventive concept, though the particular novelty resides more specifically in the hanger bracket or means for accommodating and attaching the flashlight.

Other features and advantages will become more readily apparent from the following description and drawings.

30 In the drawings, wherein like numerals are employed to designate like parts throughout the views:

Figure 1 is a side elevational view of the conventional roller skate with the improved flashlight accommodation and hanger device in place.

35 Figure 2 is a bottom plan view of the assemblage seen in Figure 1 with the dancing shoe omitted.

Figure 3 is a longitudinal sectional view on the 40 plane of the line 3—3 of Figure 2.

Figures 4 and 5 are sectional views on the vertical and horizontal lines 4—4 and 5—5 respectively of Figure 3.

45 Figure 6 is what may be conveniently called a top plan view with the device detached from the skate and the flashlight removed therefrom.

Figure 7 is a perspective view of a spring retaining clip for the flashlight.

In the drawings, in Figures 1 and 2 the conventional roller skate is generally denoted by the 50 numeral 8. Generally it embodies the customary plate or frame 9 and rollers or wheels 10. It is unnecessary, however, to go into any detail concerning the construction of the skate for applicant, makes no claim thereto, except insofar as

it relates broadly to the combination of a self-contained source of illumination hung and depending therefrom at points between the front and rear wheels.

As before indicated, the source of illumination 5 in the instant case may of course be any suitable device, but it is here represented in the form of a spot type flashlight 11. This is any conventional style and includes a handily located switch 12. The bulb itself is indicated at 13 and this 10 is suspended in such a way as to flash the light rays downwardly between the front and rear sets of rollers. To accomplish this I employ a stirrup-like hanger bracket or fixture 14. The flashlight is saddled in this and the fixture is 15 hung or suspended from the frame of the skate. As is evident, the bracket 14 is of general U-shaped form and its bight portion 15 has an aperture 16 therein to accommodate the bulb 13. The vertical parallel side walls 17 have their upper ends narrowed and formed into inturned 20 retention hooks 18, these being resilient and adapted to snap over the longitudinal edges of the skate frame, as brought out to advantage in Figure 4.

25 The flashlight is held removably and against displacement in the stirrup through the instrumentality of a spring clip 19, this having bent ends 20 bearing releasably against the adjacent side of the flashlight as brought out effectively 30 in Figures 3 and 4. The retention clip is centrally riveted as at 21 to a lightweight filler and backing member 22 which is in turn attached to and maintained in place by an adapter plate 23. The part 23 has downturned ends riveted to the 35 parallel sides of the main hanger as shown in Figure 4. The adapter plate also serves to support a complementary bracket 24, this having an upstanding end portion 25 apertured and screw-threaded to accommodate the shank 26 of the 40 set-screw 21. The set-screw forms a stop element and exerts a thrust against the bendable upper end portion of the adjacent flange on the hanger. In other words, in order to maintain the hooked flanges in place, one cannot always 45 depend on the inherent resiliency. This is due to the fact that the skates might vary in width and there may be times when it is necessary to take up the play. This play is adjusted by the thrust screw 27 coacting with the lug 28 on the bracket 50 24. This is of course, an incidental feature but is nevertheless a safety device to facilitate securely maintaining the invention in place on the skate. The main idea however, is to provide a stirrup-like hanger to detachably connect with 55

In the drawings, in Figures 1 and 2 the conventional roller skate is generally denoted by the 50 numeral 8. Generally it embodies the customary plate or frame 9 and rollers or wheels 10. It is unnecessary, however, to go into any detail concerning the construction of the skate for applicant, makes no claim thereto, except insofar as

the skate, to utilize it to support a flashlight, and to employ means in the hanger for releasably holding the flashlight in place, whereby it is possible to remove the flashlight and replace the 5 battery independent of removal of the hanger device itself. Chiefly, however, I am concerned with a hanger for a flashlight where it is possible to securely maintain the flashlight on the roller skate while dancing or maneuvering in 10 skating ring exhibitions and the like.

It is thought that the description taken in connection with the drawings will enable a clear understanding of the invention to be had. Therefore, a more lengthy description is thought 15 unnecessary.

While the preferred embodiment of the invention has been shown and described, it is to be understood that minor changes coming within the field of invention claimed may be resorted to 20 if desired.

I claim:—

1. In a construction of the class described, a roller skate comprising a frame embodying front and rear rollers, and a source of illumination supported on the frame between said front and rear rollers, and depending from said frame in a position to focus the light beam on the floor.

2. In a construction of the class described, in combination, a roller skate including a frame and front and rear supporting rollers, a flashlight, and a hanger constituting a holder, said hanger being constructed for detachable connection with the frame at a point between the front and rear rollers and being designed to dispose the light 35 beams for flashing on the floor.

3. A skate attachment of the class described comprising a stirrup for supporting a flashlight, said stirrup being U-shaped in form and the

bight portion thereof having a central aperture to expose the bulb of the flashlight, and means for detachably and adjustably connecting said stirrup with the frame of a conventional roller skate.

4. A roller skate attachment of the class described comprising a U-shaped stirrup to accommodate a flashlight including an apertured bight portion and parallel attaching flange portions with the free ends of the flanges being formed into resilient retention hooks, an adapter plate between said flanges, a clip thereon to releasably engage the flashlight, and an adjustable connection between the adapter plate and one of said flanges for flexing the same to facilitate 15 adjustment and maintenance.

5. In a structure of the class described, a roller skate comprising a horizontally elongated frame provided on its bottom with conventional front and rear longitudinally spaced rollers, and a manually controllable self-contained source of illumination supported on the under side of said frame and located midway between the front and rear rollers and adapted to project light rays on the floor at approximate right angles to said 20 frame.

6. In a structure of the class described, a roller skate structure comprising a horizontally elongated foot plate provided on its bottom with longitudinally spaced front and rear conventional 30 rollers, a manually controllable detachable and repairable flashlight, and means for operatively attaching the flashlight to said plate at a point midway between the front and rear rollers to occupy a position beneath and parallel to the 35 plate and to focus light rays on the floor.

MIKALY GALGOCZY.
